CLAIM

The ornamental design for a light fixture, as shown and described.

DESCRIPTION

This application contains subject matter which is related to the subject matter of the following application, which is hereby incorporated herein by reference in its entirety: Ser. No. 29/276,638, co-filed herewith.

FIG. 1 is perspective view of the light fixture of the present invention;

FIG. 2 is a front elevation view thereof;

FIG. 3 is right side elevation view thereof, the left side elevation view being a mirror image thereof;

FIG. 4 is a rear elevation view thereof;

FIG. 5 is a top plan view thereof; and,

FIG. 6 is a bottom plan view thereof.

The broken line showing is for illustrative purposes only and forms no part of the claimed invention.
